Primary Examiner — Patricia Palasik(74) *Attorney, Agent, or Firm* — Patterson Thuente
Christensen Pedersen, P.A.**CLAIM**The ornamental design for a hole cutter, as shown and
described.**DESCRIPTION**FIG. 1 is a front perspective view of a hole cutter of the
present design;

FIG. 2 is a rear perspective view thereof;

FIG. 3 is a front view thereof;

FIG. 4 is a rear view thereof;

FIG. 5 is an enlarged top plan view thereof;

FIG. 6 is an enlarged bottom plan view thereof;

FIG. 7 is a right side view thereof;

FIG. 8 is a left side view thereof; and,

FIG. 9 is an enlarged cross-sectional view taken along line 9-9
in FIG. 3.The broken lines are shown for illustrative purposes only and
form no part of the claimed design. The dashed-dotted lines
denote the boundary of the claim and form no part of the
claimed design.**1 Claim, 9 Drawing Sheets****US D656,168 S**
